UNITED STATES PATENT OFFICE.

WARREN NOBLE, OF DETROIT, MICHIGAN.

INTERNAL-COMBUSTION ENGINE.

1,208,359.

Specification of Letters Patent. Patented Dec. 12, 1916.

Application filed November 1, 1915. Serial No. 58,957.

To all whom it may concern:

Be it known that I, WARREN NOBLE, a subject of the King of Great Britain and Ireland, residing at Detroit, in the county 5 of Wayne and State of Michigan, have invented certain new and useful Improvements in Internal-Combustion Engines, of which the following is a specification, reference being had therein to the accompanying drawings.

The invention relates to internal combustion engines, and has for its primary object the obtaining of a construction which will operate successfully for long periods of 15 time with little attention.

To this end the invention comprises, first, the novel construction and arrangement of parts by which lubrication of the moving parts is maintained; further, the construction 20 of the valve and means for lubricating the same; and further, various features of construction as hereinafter set forth.

In the drawings: Figure 1 is a vertical central section through the engine; Fig. 2 25 is a section in a plane at right angles to Fig. 1; and Fig. 3 is a sectional plan view, on line α — α Fig. 1.

A is the engine cylinder, provided with a suitable water jacket B, preferably integral therewith, and also provided with 30 the inlet and exhaust ports C and D.

E is a cylindrical valve sleeve, which is 35 rotatably secured within the cylinder A, being provided with suitable driving means, such as the spiral gear F at its lower end.

G is an inner core member fitting within 40 that portion of the sleeve E which covers the inlet and exhaust ports and being hollow to form a water jacket. The member G is provided with ports H and I, which are respectively in registration with the inlet and exhaust ports C and D. J is a 45 shouldered portion for fitting within the upper end of the cylinder to hold the core in axial alinement therewith.

K is a flange resting upon the end of the cylinder, and L is a centrally-projecting threaded nipple for receiving the spark plug. This nipple is provided with a shoulder M which is engaged by a detachable 50

head N secured to the end of the cylinder and forming a connecting water chamber between that in the core member and the jacket surrounding the cylinder.

With the construction as thus far described it will be understood that the sleeve E rotates in the annular space between the inner core member G and the outer cylinder A, and as this sleeve is provided with ports E' they will be periodically registered with the inlet and exhaust ports. One difficulty encountered with such a construction is to properly lubricate the portion of the sleeve which is intermediate the core and the outer cylinder, and this difficulty I have avoided 65 by the peculiar construction of piston and its co-operative relation to the sleeve and the core. As shown N' is the piston which is provided on one side with a tapering upward projection O extending to a point 70 above the ports C and D when said piston is at the upper end of its stroke. To provide clearance for this upward projection O the core member G is cut-away at one side, as indicated at P, so that the core and piston are complementary to each other and together fill the cylinder, with only sufficient clearance for the compressed explosive gases. By reason of this construction the lubricant which is supplied to the cylinder 80 is carried up by the sweeping action of the extension O, while the rotation of the sleeve E will carry the lubricant around the core member G, thereby thoroughly lubricating all of the working surfaces. In addition 85 to this function the extension O forms a seal for one of the ports E' of the sleeve E, during the latter portion of the compression stroke and the early portion of the working stroke. Still another function is that it 90 forms a long bearing for the piston for preventing the skewing action in the cylinder.

In operation, the sleeve E is preferably 95 rotated in a one to four ratio to the crank shaft speed, so that the diametrically opposite ports E' in said sleeve are alternately brought into operation. Each upward stroke of the piston carries the extension O to above the ports and each eighth stroke will complete the rotation of the sleeve. The 100

explosive charge is compressed in the clearance space between the piston and core member as well as that within the central chamber of the core surrounding the spark

5 plug. The water chamber within the core absorbs the excessive heat of explosion and protects the sleeve therefrom, while the portion of the sleeve not protected by the core is shielded by the piston and the upward 10 extension O thereof.

To supply the lubricant to the inner and outer faces of the sleeve I have devised the following construction: Q is the crank case connecting with the cylinder, which has

15 formed thereon a thrust bearing Q' for the lower end of the sleeve E, and above said bearing an annular pocket Q² for receiving the annular gear F. R is a pinion intermeshing with the gear wheel F and ar-

20 ranged in a pocket R' within the crank case, communicating with the annular pocket Q'.

S is a drive shaft for the pinion which is hollow and has arranged therein the check valve S', preferably a ball held to its seat 25 by a spring S² and threaded collar S³. This shaft is driven preferably by spiral gearing from the crank shaft T, which is hollow and is provided with a crank T' having a channel T² therein communicating through

30 a channel T³ in the crank pin T⁴ with a hollow pitman rod U. This rod at its upper end connects with a hollow wrist pin U' extending through the piston N, and the arrangement is such that they form a con-

35 tinuous channel for lubricant from the hollow crank shaft to the surface of the piston, where it is distributed on the inner face of the sleeve.

For forcing the lubricant through the 40 hollow shaft S and channeled connections to the piston a suitable pump is provided, preferably a gear pump V mounted on the shaft S. The discharge end of this pump has communication with the hollow shaft S,

45 through which lubricant is supplied to the pockets R' and Q² and distributed from the latter around the outer face of the sleeve. Another distributing channel W extends from the pump through the bearing for the

50 crank shaft and through ports in the latter to the hollow interior, from which it is distributed through the hollow connections to the piston. Thus the sleeve is thoroughly lubricated both inside and out, and waste of

55 the lubricant is prevented by the sealing connection formed by the thrust bearing Q' and by the seal of the piston rings. The lubricant which escapes from the bearing or crank shaft is recovered by a cup-shaped oil

60 guard X, which is secured to the hub of the fly wheel X', and has a flange X² extending within a channel X³ in a stationary portion of the bearing. Thus whatever lubricant escapes will be thrown outward by centrifugal action, filling around the flange X²

and accumulating in the channel X³, from which it is returned to the holding tank.

What I claim as my invention is:—

1. In an internal combustion engine, the combination with a ported cylinder of a 70 rotative sleeve within said cylinder ported for registration with said cylinder port, a piston member and a core member fitting within different portions of said sleeve, a segmental projection on one of said members overlapping the ported portion of said sleeve and forming an inner seal therefor, and means upon the other of said members for lubricating the inner face of said sleeve adjacent to said segmental projection. 75

2. In an internal combustion engine, the combination with a ported cylinder of a rotative sleeve within said cylinder ported for registration with the cylinder port, a reciprocatory piston member and a core 85 member fitting within different portions of said sleeve, a segmental extension of said core member overlapping the ported portion of said sleeve and forming an inner seal 90 therefor, and a segmental extension of said piston adapted to overlap an adjacent portion of said sleeve and forming lubricating means therefor.

3. In an internal combustion engine, the combination with a ported cylinder, of a 95 rotative sleeve within said cylinder ported for registration with said cylinder port, a piston reciprocating within said sleeve, having an upward extension on one side thereof, and a core member extending within 100 said sleeve and cut-away to be complementary to the upward extension of said piston.

4. In an internal combustion engine, the combination with a ported cylinder, of a rotative sleeve therein ported for registration with the cylinder ports, a core member within said sleeve extending to cover the ported zone of said cylinder and provided with a registering port, said core being cut-away on one side beyond the zone of the ports, and a piston reciprocating within said sleeve below said core member and provided with an upward extension complementary to the cut-away portion of said core member. 110

5. In an internal combustion engine, the combination with a cylinder having inlet and exhaust ports in a zone thereof, of a rotative sleeve within said cylinder having a plurality of ports successively registered with said inlet and exhaust ports, a core member fitting within the ported zone of said sleeve and cut-away at one side, and a piston reciprocating within said sleeve, having an extension complementary to said cut-away portion of the core, said extension adapted to cover one of the ports of said sleeve. 115

6. In an internal combustion engine, the combination with a ported cylinder, of a rotative sleeve within said cylinder ported 120

for registration with the cylinder port, a reciprocatory piston within said sleeve, a crank and pitman connection to said piston, a rotative drive connection for said sleeve, and lubricating means for the inner and outer surfaces of said sleeve connected respectively with channels in said crank, pitman and piston and through said rotary drive connection.

10 7. In an internal combustion engine, the combination with a ported cylinder of a sleeve therein ported for registration with the cylinder port, an annular gear at the lower end of said sleeve, a thrust bearing on
15 said cylinder for the end of said sleeve below said gear, a pinion meshing with said gear in a pocket in said cylinder above said bearing, a hollow shaft on which said pinion is mounted, and means for forcing lubricant
20 through said hollow shaft into said pocket and distributing the same between said sleeve and cylinder, said thrust bearing forming a seal for the lubricant.

8. In an internal combustion engine, the
25 combination with a ported cylinder of a ro-
tative sleeve therein ported for registration
with the cylinder port, an annular gear at
the lower end of said sleeve engaging an an-
nular chamber within said cylinder, a pin-
30 ion intermeshing with said gear in a pocket
communicating with said annular chamber,
a hollow shaft for said pinion, and means
for forcing lubricant through said hollow
shaft, through said pocket and annular
35 chamber and distributing from the latter
between the surfaces of said sleeve and cyl-
inder.

9. In an internal combustion engine, the combination with a ported cylinder, of a rotative sleeve therein ported for registration with the cylinder port, an annular gear at the lower end of said sleeve, a crank case connecting with the lower end of said cylinder, a thrust bearing in said crank case for 40 engaging the lower end of said sleeve and having an annular channel above the same for receiving said gear wheel, a pinion intermeshing with said gear wheel in a pocket in said crank case, communicating with said 45 annular channel, a hollow shaft for said pinion, and means for forcing lubricant through said hollow shaft and pinion into said pocket and distributing the same around said annular channel and between the surfaces of said 50 sleeve and cylinder.

10. In an internal combustion engine, the combination with a cylinder and a rotative sleeve therein, of a hollow drive connection for said rotative sleeve, and means for forcing lubricant through said hollow drive connection between said sleeve and cylinder.

11. In an internal combustion engine, the combination with a cylinder and a rotative

sleeve therein, of an annular gear at the lower end of said sleeve engaging an annular pocket in the engine casing, a pinion intermeshing with said gear, a hollow shaft on which said pinion is mounted, means for driving said shaft, and a rotary pump also mounted on said shaft for forcing lubricant through the same into said annular chamber and between said sleeve and cylinder. 65 70

12. In an internal combustion engine, the combination with a casing, of a rotative sleeve therein, an annular gear at the end of 75 said sleeve engaging an annular pocket within said casing, a pinion intermeshing with said gear, a pocket communicating with said annular pocket, a hollow shaft for 80 said pinion, a check valve in said hollow shaft, and a rotary pump mounted on said hollow shaft for forcing lubricant through the same past said check valve into said annular chamber and between said sleeve and casing. 85

13. In an internal combustion engine, the combination with the engine casing including the cylinder, of a rotative sleeve within said cylinder, a reciprocatory piston within said rotative sleeve, an annular gear at the lower end of said sleeve engaging an annular pocket in said engine casing, a pinion intermeshing with said gear within a pocket in said casing communicating with said annular pocket, a hollow shaft for said pinion, a crank shaft, a drive connection between said crank shaft and hollow shaft, a rotary pump on said hollow shaft having its discharge communicating with the channel through said shaft, a lubricant tank, and a suction conduit from said pump depending therefrom into said lubricant tank.

14. In an internal combustion engine, the combination with an engine casing including a cylinder and crank case, of a rotative sleeve within said cylinder, a reciprocatory piston within said sleeve, an annular gear at the lower end of said sleeve engaging an annular pocket in said casing, a hollow drive connection for said annular gear, a lubricant pump mounted on said hollow drive connection for forcing a portion of the lubricant therethrough into said annular pocket and between said sleeve and cylinder, a crank shaft operatively connected to said hollow drive connection and having a lubricant channel therein, a channeled crank and pitman connection to said reciprocatory piston, and connections for distributing a portion of the lubricant from said pump through said hollow crank shaft and hollow connections to said piston for lubricating the inner surface of said sleeve. 105 110 115 120

15. In an internal combustion engine, the combination with a ported cylinder of a 125 rotative sleeve within said cylinder ported

for registration with the cylinder port, a reciprocatory piston member and a core member fitting within different portions of said sleeve, and a segmental extension of said piston member adapted to overlap a ported portion of said sleeve and forming lubricating means therefor.

Copies of this patent may be obtained for five cents each, by addressing the "Commissioner of Patents, Washington, D. C."

In testimony whereof I affix my signature in presence of two witnesses.
